UNITED STATES PATENT OFFICE.

EDGAR ERIC TATE, OF EDEN, TEXAS.

GIN-BREAST LIFTER.

Application filed May 10, 1927. Serial No. 190,241.

My invention relates to automatic lifting devices for breasts for cotton gins and has for an object to raise the breast out of ginning position should the machine become choked by an accumulation of lint or otherwise to perfectly function from any cause as by the saws becoming clogged for the brushes failing to properly clean the same.

Under such conditions, should the machine 10 continue to the operation, the lint cotton becomes tightly wedged between the ribs 6 coming into contact with the rapidly revolving saws, frequently tends to ignite the same often resulting in serious damage by fire.

15 My invention therefore contemplates the provision of means whereby when such defective working of the gin occurs the gin breast will be automatically lifted from the saws so that they will no longer be in operative contact with the cotton, and the feeding of the cotton to the saws will be stopped.

Other objects and advantages reside in the special construction, combination and arrangement of the various elements forming 25 the invention, as more fully hereinafter described and claimed, reference being had to the accompanying drawings forming part thereof, wherein like numerals refer to like parts throughout and in which:—

30 Figure 1 is a perspective view of my device in operative position upon a gin frame.

Fig. 2 is a view of the breast lifting arm.

Fig. 3 is an end view showing the relative 35 position of the saw ribs and breast lifting cam, and

Fig. 4 is a detail of the saw ribs.

Referring now to the drawings, I have shown my invention adapted for use upon 40 a ginning machine comprising a frame 5 upon which is transversely mounted the usual cylindrical saw set 6, the blades of which are arranged in spaced relation. Immediately beneath the saw is arranged a trans- 45 versely disposed rock shaft 7 having ribs 8 secured thereto and extending upwardly between the blades of said saw. The shaft is suitably mounted in bearings 9, with one end thereof provided with a crank 10, the 50 end of the crank being inserted in the block 11 formed in a lever 12 pivotally mounted intermediate its ends upon a bracket 13.

One end of the lever is provided with a 55 downwardly depending pin 14 slidably ar- ranged in a vertically disposed guide 15 and

having its end adapted to be inserted in notches 16 formed in a rod 17 slidably supported in a bore provided in the guide. A coiled spring 18 connects the lever to a stationary part of the frame so as to normally maintain the pin within one of the said notches.

At one end of the rod 17, I attach the flange 19 having its forward end attached to a block 20, slidably arranged on a bracket 21 secured to the frame, the blocks thereby being adjustably arranged on the bracket so as to regulate the tension of the spring. A link 22 is attached to the opposite end of the sliding rod 17 within which is formed a 70 groove 23 and within which a pin 24 carried on an arm 25 is adjustably secured.

The arm 25 is fixedly secured to one end of a rock shaft 26 which extends transversely of the frame, and has its opposite end 27 75 rotatably trained in a bearing 28 and provided with a breast lifting cam 29.

The cam 29 engages the lower end of a gin breast 30, the upper end of which is hingedly secured to the frame as at 31. 80

A hand lever 32 is arranged on the end of the rock shaft 26 opposite from the cam whereby the same may be returned to normal operative position as hereinafter explained.

With the device in normal operative position, the breast will occupy a position as shown by Fig. 3 of the drawing, the position of the ribs 8 under such circumstances, being shown in full lines. Should lint accumulate between the blades of the saw, the 90 ribs will be gradually forced into a position as shown by the dotted lines in Fig. 3, thereby turning the rocking shaft 7 operating through the crank 10 and lever 12 to raise the pin 14 out of engagement with the rod 17 which is thereby released and causing the cam 29 to move out and downwardly so as to raise the gin breast out of position.

While I have described an operative form of my invention, I desire it to be understood 100 that I do not wish to limit myself to the particular construction shown therein as various changes and modifications may be made without departing from the spirit of the invention, or the scope of the appended 105 claims.

Having thus described my invention, what I claim as new is:—

1. In an apparatus of the character de- 110 scribed, whereby to control the operation of

a gin under certain predetermined conditions, a rock shaft having a cam adapted to engage the gin breast, a slidably mounted rod attached to said shaft, means for normally securing said rod and means for releasing said securing means, whereby to throw the breast out of ginning position.

2. In a gin breast lifting attachment, a rock shaft having a cam adapted to engage 10 the gin breast, a slidably mounted rod, a link connecting said rod and said shaft, spring means adapted to operate said rod, a pin normally restraining the movement of said 15 rod, and means for removing said pin out of engagement therewith, whereby to cause the actuation of the rock shaft for throwing the breast out of ginning position.

3. In a gin breast lifting attachment a rock shaft having a cam adapted to engage 20 the gin breast, a slidably disposed rod, a link connecting said rod with said shaft, spring means adapted to operate said rod, notches formed in said rod, a pin adapted to be inserted in said notches, a rock shaft 25 having a plurality of ribs mounted thereon, said shaft being actuated through pressure upon said ribs, and a lever operatively connecting said pin and said shaft, whereby under certain predetermined conditions to cause the actuation of said first named rock 30 shaft for throwing the breast out of ginning position.

4. In a gin breast lifting attachment, a rock shaft having a cam arranged thereon and adapted to engage the gin breast, a slidably mounted rod, a link connecting said rod and said shaft, spring actuating means for said rod, notches formed in said rod, a bracket for said rod having a vertically

disposed bore, a pin slidably mounted in 40 said bore and adapted to engage said notches, a rock shaft having a plurality of ribs adapted to actuate said shaft, and responsive to certain predetermined ginning conditions, and a lever pivotally mounted intermediate its ends having one end thereof attached to said last-named rock shaft, and its opposite end attached to said pin, and adapted through the actuation of said rock shaft to release the pin whereby to throw 50 the breast out of ginning position.

5. In a gin breast lifting device, a rock shaft having a cam arranged thereon and adapted to engage the gin breast, a slidably mounted rod, a link connecting said rod and said rock shaft, spring actuating means for said rod, means for tensionally adjusting said springs, a bracket slidably supporting said rod and having a vertically disposed guide formed therein, notches in said rod, 60 a pin slidably mounted in said guide and adapted to engage said notches, means for normally retaining said pin in engaged position, a rock shaft having a plurality of ribs adapted to actuate the same and responsive to certain predetermined ginning conditions, a crank formed at one end of 65 said rock shaft, and a lever pivotally mounted intermediate its ends and having one end secured to said crank and the opposite end attached to said pin and adapted through the actuation of said rock shaft to release the pin whereby to throw the breast out of 70 ginning position.

In testimony whereof I affix my signature.

EDGAR ERIC TATE.
